VALET STAND

Clarence D. Zierhut, Granada Hills, Calif., assignor to The Cal-Dak Company, Los Angeles, Calif., a corporation of California

Filed Feb. 27, 1964, Ser. No. 78,806

Term of patent 14 years

(Cl. D33—8)

FIG. 1 is a perspective view of a valet stand embodying my new design;

FIG. 2 is a side elevational view of the valet stand; and

FIG. 3 is a front elevational view thereof.

I claim:

The ornamental design for a valet stand, as shown.
